UNITED STATES PATENT OFFICE.

DWIGHT S. RICHARDSON, OF NEW YORK, N. Y.

DESIGN FOR A GRATE-BAR.

SPECIFICATION forming part of Design No. 33,923, dated January 15, 1901.

Application filed December 3, 1900. Serial No. 38,572. Term of patent 14 years.

To all whom it may concern:

Be it known that I, DWIGHT S. RICHARDSON, a citizen of the United States, residing at New York, in the county of New York and State of New York, have invented and produced a new and original Design for a Grate-Bar; and I do hereby declare the following to be a full, clear, and exact description of the same, reference being had to the accompanying drawings, forming a part thereof.

My invention is a new and useful design for a grate-bar; and it consists in the novel features hereinafter described with reference to the accompanying drawings, in which—

15 Figure 1 is a perspective view of my design. Fig. 2 is a sectional view of my design.

My design consists of a grate-bar having a

face A and a convex or outwardly-curved face B extending angularly therefrom, the said curved or convex face being provided with a 20 projection C, extending outwardly at an angle to said face B and located adjacent to the junction of faces A and B.

What I claim, and desire to secure by Letters Patent, is—

25 The design for a grate-bar herein shown and described.

In testimony whereof I affix my signature in presence of two witnesses.

DWIGHT S. RICHARDSON.
